UNITED STATES PATENT OFFICE

170,510

COFFEE MAKER

Samuel J. Popeil, Chicago, Ill.

Application December 6, 1952, Serial No. 22,584

Term of patent 3½ years

(Cl. D44—26)

To all whom it may concern:

Be it known that I, Samuel J. Popeil, a citizen of the United States, resident of Chicago, in the county of Cook and State of Illinois, have invented a new, original, and ornamental Design for a Coffee Maker, of which the following is a specification, reference being had to the accompanying drawing, forming a part hereof, wherein:

Fig. 2 is a top plan view.

Fig. 3 is a bottom view of the coffee maker with the bottom cap removed.

Fig. 4 is a fragmentary sectional view taken substantially along line 4—4 in Fig. 2.

Figs. 5 and 6 are fragmentary detailed sectional views taken respectively along lines 5—5 and 6—6 of Fig. 1.

Fig. 7 is a fragmentary perspective view of the bottom cap of the coffee maker shown in the preceding figures.

I claim:

The ornamental design for a coffee maker, substantially as shown.

SAMUEL J. POPEIL.
